No. 657,534.

Patented Sept. 11, 1900.

M. HABERLE.

WINDOW.

(No Model.)

(Application filed Apr. 4, 1900.)

UNITED STATES PATENT OFFICE.

MICHAEL HABERLE, OF NEW YORK, N. Y.

WINDOW.

SPECIFICATION forming part of Letters Patent No. 657,534, dated September 11, 1900.

Application filed April 4, 1900. Serial No. 11,522. (No model.)

To all whom it may concern:

Be it known that I, MICHAEL HABERLE, a citizen of the United States, residing at New York, (Brooklyn,) in the county of Kings and State of New York, have invented certain new and useful Improvements in Windows; and I do hereby declare the following to be a full, clear, and exact description of the invention, such as will enable others skilled in the art to which it appertains to make and use the same.

This invention has relation to windows, and more particularly to the class having the sash pivoted or hinged to counterbalanced slides mounted in the casement for vertical movements, and is designed specifically as an improvement on the construction set forth in Letters Patent No. 645,357, granted to me March 18, 1900.

20 The purpose of the invention is to secure a close joint between the slides and the side stiles of the sash, so as to exclude wind, rain, snow, and dust, and to improve the connections to the attainment of strength and the 25 provision of means for positively taking up any space.

The improvement consists, essentially, of the novel features, details of construction, and combinations of the parts which herein- 30 after will be more particularly set forth, illustrated, and finally claimed.

In the drawings forming a part of the application, Figure 1 is a perspective view of a 35 slide and the adjacent portion of the sash pivoted thereto, showing the relation of the parts when the sash is lowered or turned into an approximately-horizontal position. Fig. 2 is a vertical section of the parts illustrated in Fig. 1. Fig. 3 is a transverse section about 40 on the line X-X of Fig. 2. Fig. 4 is a detail perspective view of one member of the fastening for the swing end of the sash. Fig. 5 is a similar view of the other member. Fig. 6 is a transverse section on the line Y-Y of 45 Fig. 2. Fig. 7 is a detail perspective view of the slide-block, showing a portion of the brace applied thereto. Fig. 8 is a detail view showing another way of forming the plate which is attached to the upper member of the slide-block.

50 Corresponding and like parts are referred to in the following description and indicated

in all the views of the drawings by the same reference characters.

The slide 1 is provided with a longitudinal 55 slot 2 to receive the block 3, mounted for sliding movements therein and to which the counterbalanced rope or cord 20 is attached. The sash 4 is pivoted at its lower end to the slide 1 and is limited in its downward movement by the brace 5, which is pivotally connected at one end to the block 3 and at its opposite end to the side stile 6 of the sash 4. A plate or washer 7 is let into the side stile 6 and receives the wear of the screw 8, by 60 means of which the brace 5 is pivotally connected to the said stile.

The hinge-joint between the slide 1 and sash consists of the hinge members 9 and 10 and the screw 11, the latter constituting the 70 pivot upon which the members 9 and 10 turn and by means of which the slide 1 and sash are drawn together, so as to prevent the formation between their opposing sides of any appreciable space. The hinge members 9 and 10 are enlarged at their lower or pivotal ends to provide sufficient bearing for the pivot-fastening 11. The member 9 is let into the outer side of the slide 1 and the member 10 is mortised into the stile 6. The screw 11 75 has its head countersunk in the outer side of the hinge member 9 and its inner end makes screw-thread connection with the stile 6, and by a proper adjustment of the screw the opposing faces of the parts 1 and 6 may be 80 drawn more or less closely together.

The sash when closed is held at its swing end against casual displacement by means of a fastening comprising complementary members or parts, one being secured to the slide 90 and the other to the stile 6. These members are similarly formed, and consist of plates 12, provided with openings to receive the screws or fastenings by means of which they are attached to the respective parts with which they 95 coöperate. Each plate is formed with a facial projection 13 of wedge form, located centrally at one side, the side or edge portion opposite the projection 13 being cut away, as shown at 14, to accommodate the projection 13 100 of the opposite plate when the two members are brought together. The inner ends of the projections 13 overhang the inner ends of the notches or cut-away portions 14 and are bev-

eled upwardly and outwardly, as shown at 15, and these beveled ends are adapted to ride upon each other and draw the plates or members of the fastening together when closing 5 the sash against the slide. The notches or cut-away portions 14 are outwardly flared in conformity to the taper of the projections 13, so as to receive the latter when the parts are coupled. One of the plates or members of the 10 sash-fastening is provided with an opening or depression 16 and the other plate or member is supplied with a spring-actuated catch 17, having its projecting end made rounding and adapted to enter the opening 16 and hold 15 the sash against casual displacement until sufficient force is applied thereto to cause the projecting end of the cap 17 to ride out of the opening or depression 16. Positive locking means may be combined with the fastening 20 to prevent the opening of the sash by the application of lateral force thereagainst, and this fastening, as shown, consists of a pin 18, slidingly mounted in an opening of the stile 6 and adapted to pass through registering open- 25 ings 19, provided in the plates or members 12.

The parts being assembled substantially as shown in Figs. 1 and 2 and it being required to take up the space between the slide 1 and the stile 6 the screw 11 is turned more or 30 less to attain the desired end, and when the sash is closed against the slide the inclined or beveled ends of the offstanding facial projection 13 ride upon each other and draw the parts together by a wedging action. For ordinary purposes the spring-actuated catch 17 will hold the sash closed, but when it is required to lock the sash the pin 18 is pressed inward through the openings 19 of the plates or members of the sash-fastening.

40 In order to facilitate repair and admit of the proper positioning of the counterbalanced rope, chain, or analogous device, the slide-block 3, to which said part 20 and the brace 5 are attached, has the side facing the window-opening removed. This slide-block comprises an outer member 21 and lateral branches 22 and 23, projecting from the part 21 in parallel relation. The brace 5 is pivotally connected to the lower part 23 of the slide-block by means of a screw or pivot-fastening 24, and the part 22 is formed with an opening 25 to receive the rope 20, which is passed therethrough and has its lower end formed into a knot 26 to prevent the withdrawal of the engaging end of the rope from the slide-block when connected thereto. The parts 22 and 23 are of less width than the part 21, which latter has its vertical edge portions overlapping the rear side of the slide 55 1. A sufficient distance to prevent outward displacement of the slide-block toward the window-opening. A plate or cap 27 is secured to the outer end of the part 22 and its end portions overlap the front side of the slide-block and act jointly with the brace 5 to prevent rearward displacement of the slide-block. This cap 27 is secured to the part 22

by a screw or fastening 28 and is prevented from turning upon said fastening by a rear projection 29, entering a notch 30 in the outer 70 end of the part 22. The front side of the slide-block being open it will be readily understood that the rope 20 may be passed through said open side and the opening 25 of the part 22 without requiring the removal of either the slide or the slide-block for this purpose. The construction just described admits of the parts being readily assembled and of repairs being easily, cheaply, and quickly effected, and in these respects is of material advantage. 80

The plate 27 may have spaced rear extensions 29^a to embrace the top and bottom sides of the part 22 to prevent its turning upon the fastening 28. This construction is shown most clearly in Fig. 8.

Having thus described the invention, what is claimed as new is—

1. In a window, and in combination with a slide and a sash pivoted thereto, a fastening comprising complementary members or parts 90 secured, respectively, to the slide and sash, each member having an offstanding projection provided with an inclined end and a notched or cut-away portion opposite said projection, the notch of one member being 95 adapted to receive the projection of the opposite member, substantially as set forth.

2. In a window, the combination with a slide and a sash pivoted thereto, of a fastening comprising complementary members secured, respectively, to the swing end of the sash and the corresponding end of the slide and formed with interlocking projections having co-operating beveled portions, and a spring-actuated catch applied to one of the members and 105 adapted to enter an opening or depression in the opposite member, substantially as set forth.

3. In a window, the combination with a slide and a sash pivoted thereto, of a fastening 110 comprising complementary parts applied, respectively, to the swing end of the sash and the corresponding end of the slide, a spring-actuated catch applied to one of the members and adapted to co-operate with the opposite 115 member, and a locking-pin for securing both of said members, the latter being provided with offstanding projections having beveled interlocking parts, substantially as set forth.

4. In a window and in combination with a slide and a sash pivoted thereto, a slide-block having the side facing the window-opening open and its top portion formed with an opening to receive the counterbalance connection, and a brace connecting the lower portion of 120 the slide-block with the sash, substantially as set forth.

5. In a window, and in combination with a slide and a sash pivoted thereto, of a slide-block applied to the slide and having the side 130 facing the window-opening open and its top part formed with an opening to receive the counterbalance connection which is insertible through the said open side of the slide-

block, and a brace pivotally connected at one end to the lower portion of the slide-block and having similar connection at its opposite end with the sash, substantially as specified.

5 6. In a window and in combination with the slide and the sash pivoted thereto, of a slide-block comprising an outer member and horizontal space members; the upper horizontal member having an opening to receive the counterbalance connection; a cap applied to

the outer end of the horizontal member having the opening, and a brace pivotally connected with the lower horizontal member of the slide-block, substantially as specified. 15

In testimony whereof I affix my signature in presence of two witnesses.

MICHAEL HABERLE. [L. S.]
